UNITED STATES PATENT OFFICE

RUDOLF SCHNABEL, OF BERLIN, GERMANY, ASSIGNEE, BY MESNE ASSIGNMENTS, TO PYRENE-MINIMAX CORPORATION, A CORPORATION OF DELAWARE

PROCESS OF PRODUCING FOAM FROM FOAM DEVELOPING SUBSTANCES

Application filed April 23, 1927, Serial No. 186,166, and in Germany August 22, 1925.

My invention relates to a process of producing foam for extinguishing fires which have broken out in oil or gasoline tanks and similar conflagrations which cannot be extinguished by means of water.

5 My improved method consists substantially in forcing the foam generating liquid together with air or any other gas through an apparatus in which the liquid and the gas necessary for the generation of the foam are set in whirling motion or helical gyration. This whirling motion may be caused either by the liquid or by the gas passing through the apparatus or by the liquid as well as the gas in cooperation. Both agents, the liquid as well as the gas, must be introduced into the apparatus under pressure. Sometimes it may be advisable to put one medium or agent under higher pressure than 10 the other.

The whirling motion or helical gyration may be effected by any of the constructive means customary in engineering. The liquid and the gas may, for instance, be forced through a helical member located in a tube, as customary in spraying nozzles. The whirling or centrifugal motion may, however, also be brought about by conducting the liquid or the gas, for instance, compressed air, 15 through a tube provided with tangentially arranged inlets for the liquid or the gas, a thrust in the direction of the axis of the tube being exerted in addition to the helical rotation. The end in view may, furthermore, be attained by means of an apparatus which 20 operates in the manner of a jet condenser and in which the liquid is set in whirling or eddying motion, by inlet openings located under acute angles to the axis of the tube. The apparatus for producing the foam may, furthermore, be so designed that it causes a 25 whirling motion of the liquid and the gas in opposite directions or with a difference in the speed of rotation.

45 In the drawing affixed hereto are diagrammatically illustrated, by way of example, a number of devices suitable for carrying out my improved method.

In the drawing is:—

50 Fig. 1, a device constructed on the principle

of Koerting's spraying nozzle in sectional elevation,

Fig. 2, a rear view of Fig. 1 viewed from the right towards the left,

Fig. 3, a device with tangentially arranged supply nozzles for the liquid or the gas,

Fig. 4, a cross-section along line A—B of Fig. 3,

Fig. 5, a longitudinal section through a device designed on the principle of Koerting's jet condenser with an inlet branch disposed at an acute angle and tangentially to the axis of the mixing tube,

Fig. 6, a front elevation of Fig. 5 viewed from the left towards the right,

Fig. 7, a device for bringing about a gyration in opposite directions of gas and liquid, and

Fig. 8, a front elevation of Fig. 7 viewed from the left towards the right.

Referring to Figs. 1 and 2, *a* is a bottle-shaped body in which, similar to Koerting's spraying nozzle, a helix *b* is mounted axially. Into the body *a*, which is closed in the rear open supply pipes *c* and *d* for gas and liquid in a tangential direction. It will be understood, however, that the inlet points of these pipes into the body *a* might be arranged differently.

Referring to Figs. 3 and 4 of the drawing, it will be seen that the tubular device illustrated is provided with four tangentially located tube branches *f*. These tube branches are located in a drum *g* tightly fixed upon the tube *e* and provided with an inlet branch *h*.

Through the reduced end *i* of the tube *e* enters the foam-producing liquid and into the drum *g* air or gas under pressure may be introduced through the branch *h* in order to pass through the tangentially arranged pipe branches *f* into the interior of the tube *e* and to set the liquid contained therein into gyrating motion. It will be understood, however, that conversely liquid might enter through the branch *h* and compressed air through the branch *i*.

The tangentially disposed tube branches *f* are here shown as located in the same plane. They might, however, equally well be located in different planes within the drum so that they follow one another in a

helical line. In this modification an axial thrust is simultaneously developed between the currents of liquid and gas or air impinging upon one another at right angles.

5 The device illustrated in Figs. 5 and 6 of the drawing, is substantially a Koerting jet condenser *l* in which the inlet branch *k* for the liquid is located at an acute angle to the longitudinal axis of the apparatus and also 10 opens tangentially into the casing in order to bring about the desired whirling rotation or gyration. It will be understood, however, that a plurality of such inlet branches may be provided.

15 In the modification of the apparatus illustrated in Figs. 7 and 8, *m* is a drum at one side of which is provided a central outlet tube *n* for the mixture or the foam. Into this drum open in the same direction pipes *o* and *p* for the supply of the gas or the air and the liquid, these pipes being located tangentially at opposite sides of the drum, so that the currents of gas or air and liquid entering the drum perform a gyrating motion in opposite directions. The pipes *o* and *p*, which might open into the drum *m* in the same plane, are in the design illustrated located in different planes at right angles to the axis of the device. In this way one of the substances to be mixed is obliged to traverse the other substance in order to reach the outlet tube *n*, whereby a very intimate mixture of the two substances to be mixed is attained. In this device a difference in the speed of gyration of the two substances may be brought about by varying the speed with which one or the other substance enters the drum *m*.

40 In all the devices illustrated it is of course a matter of indifference as far as the principle is concerned through which of the inlets the gas, the air or the liquid enters the apparatus. It will also be understood that details of one device may be transferred to any of the others.

Various other changes and modifications may be made without departing from the spirit of my invention and the ambit of my claims and I desire, therefore, that only such limitations shall be placed thereon as are imposed by the prior art.

I claim as my invention:—

1. The process of producing foam from foam developing substances, which consists in conducting the foam generating liquid through an apparatus in which the liquid entering under pressure together with a compressed gas are both together set in whirling motion or helical gyration, the whirling effect being produced by the liquid entering under pressure and the compressed gas being passed through a tube provided with tangential inlets, in such a manner that besides the helical gyration a thrust is exerted 65 in the direction of the axis of said tube.

2. The process of producing foam from foam developing substances, which consists in conducting the foam generating liquid through an apparatus in which the liquid entering under pressure together with a compressed gas are both together set in whirling motion or helical gyration, the whirling motion being caused by an apparatus in which in the manner of a jet condenser the liquid is set in whirling rotation by means of tangential inlet branches located at acute angles to the axis of said apparatus.

3. The process of producing foam from foam developing substances, which consists in conducting the foam generating liquid through an apparatus in which the liquid entering under pressure together with a compressed gas are both together set in whirling motion or helical gyration, and in which the whirling motion caused by introduction of the liquid and the gas takes place with a difference in the speed of rotation of these two constituents.

4. The method of producing foam for fire extinguishing purposes which comprises bringing into intimate contact liquid and a gas under pressure and causing a swirling movement of the mixture by the introduction of the liquid and gas while permitting an expansion thereof.

5. The method of producing foam for fire extinguishing purposes which comprises bringing into intimate contact with a whirling motion a foam forming liquid under pressure and a gas under pressure, substantially as described.

6. An apparatus for use in forming foam for fire extinguishing purposes comprising a housing having inlets for a foam forming liquid and for a gas under pressure the inlets being arranged tangentially to cause a swirling of the gas and air at the place of entry.

7. A method of producing fire extinguishing foam which comprises separately introducing under pressure into a mixing chamber a gaseous medium and a liquid medium capable of enclosing said gas to form foam, one of said media being introduced axially of said chamber and the other of said media being introduced tangentially of said chamber to produce a whirling movement of said media resulting in the production of foam.

8. A method of producing fire extinguishing foam which comprises separately introducing under pressure into a mixing chamber a gaseous medium and a liquid medium capable of enclosing said gas to form foam, one of said media being introduced axially of said chamber and the other of said media being introduced tangentially of said chamber but in a direction having a component axial of said chamber to produce a whirling movement of said media resulting in the production of foam.

9. A method of producing fire extinguish-

- ing foam which comprises separately introducing under pressure into a mixing chamber a gaseous medium and a liquid medium capable of enclosing said gas to form foam, one of said media being introduced axially of said chamber and the other of said media being introduced tangentially of said chamber to produce a whirling movement of said media resulting in the production of foam.
- 10 10. A method of producing fire extinguishing foam which comprises separately introducing under pressure into a mixing chamber a gaseous medium and a liquid medium capable of enclosing said gas to form foam, said media being introduced tangentially into said chamber in opposite directions to produce gyrating movements of the media in opposite directions resulting in the production of foam.
- 15 11. A method of producing fire extinguishing foam which comprises separately introducing under pressure into a mixing chamber a gaseous medium and a liquid medium capable of enclosing said gas to form foam, said media being introduced tangentially into said chamber in opposite directions and in different planes to produce gyrating movements of the media in opposite directions resulting in the production of foam.
- 20 12. A method of producing fire extinguishing foam which comprises separately introducing under pressure into a mixing chamber a gaseous medium and a liquid medium capable of enclosing said gas to form foam, said media being introduced tangentially into said chamber in opposite directions and at different speeds to produce gyrating movements of the media in opposite directions and at different rates resulting in the production of foam.
